HONING TOOL

William C. Rickrode, Manchester Township, York County, Pa., assignor to York Safe and Lock Company, York, Pa., a corporation of Delaware

Application July 1, 1942, Serial No. 449,212

1 Claim. (Cl. 51—184.2)

This invention relates to honing tools and more particularly to honing tools of the type adapted to hone spiral grooves, such for instance as the rifling of guns, cannons and rifles.

An object of the invention is to provide an improved honing tool in which a plurality of abrasive elements are resiliently mounted in the body of the tool.

Another object of the invention is to provide an improved honing tool in which the body of the tool is in the form of a cylinder having a plurality of abrasive blocks arranged therearound in grooves formed lengthwise of said body at an angle with respect to the longitudinal center thereof.

Another object of the invention is to provide an improved honing tool for honing the rifling of guns, cannons and the like, in which a plurality of abrasive elements are resiliently supported in a holder adapted to be moved lengthwise of the articles to be honed.

With the foregoing and other objects and advantages in view, the invention consists in the preferred construction and arrangement of the several parts which will be hereinafter fully described and claimed.

In the accompanying drawing:

Fig. 1 is a side elevation of a honing tool constructed according to the present invention;

Fig. 2 is an end elevation of the structure shown in Fig. 1;

Fig. 3 is a transverse section taken on the line 3—3 of Fig. 1;

Fig. 4 is a longitudinal section taken approximately on the line 4—4 of Fig. 1; and

Fig. 5 is a perspective view of one of the abrasive elements.

Referring to the drawing, the improved honing tool comprises a body 11, preferably in the form of a cylinder of suitable diameter and length to slide easily in the bore of a rifle, cannon, gun, or other device which it is desired to hone.

The longitudinal center of the cylindrical body 11 may be formed with an opening 12 so that suitable means (not shown) may be secured to the tool for the purpose of operating the same.

Formed in the outer periphery of the body 11, is a series of similarly constructed grooves 13.

The grooves 13, in cross section, may be substantially rectangular in form, and said grooves may have suitable depth.

The grooves 13 extend lengthwise of the body 11, being suitably spaced apart in the manner shown best in Fig. 3.

Since the particular honing tool shown herein is adapted to be used for the purpose of finishing

or smoothing the spiral grooves of rifles, guns, cannons, and the like, as shown in Fig. 1, the grooves 13 are arranged at an angle with respect to the longitudinal center line of the body 11, so that the honing elements or blocks of abrasive material will fit properly in said spiral grooves.

If so desired, arcuate or semicircular ends 14 may be formed at each end of the grooves 13.

Mounted in each groove 13, is a block 15 of abrasive material. These abrasive elements 15 are so constructed as to be freely movable inwardly and outwardly of the grooves 13, and each block 15 may have an arcuate end 16 corresponding substantially to the ends 14 of said grooves. Since the grooves 13 are of elongated form, the abrasive blocks 15 likewise are elongated in form and said blocks have a width to snugly fit the rifling grooves so that during the operation of the tool said rifling grooves will be honed in the desired manner.

In order to resiliently support each abrasive element 15 in its groove 13, the bottom of each groove is formed with one or more recesses 17.

Mounted in each recess 17 and bearing against the bottom face of each abrasive block 15, is an expandable coil spring 18.

In Fig. 4 the device is shown as being constructed with a pair of spaced apart springs 18 under each abrasive block 15.

To limit the amount of outward movement of the abrasive blocks 15 with respect to the body 11, any suitable means may be employed. In the present instance such means is shown as comprising a pair of spaced rings 19 which encircle the tool and are mounted in alined slots 20 and 21, formed in the body 11 and in the blocks 15, respectively.

The slots 21 may be disposed adjacent to the ends 16 of the abrasive blocks 15, and the rings 19 are so arranged relative to the disposition of the springs 18 that the forces of said springs acting against the forces of said rings prevent the abrasive blocks 15 from rocking upwardly and downwardly lengthwise of the grooves 13. In other words, the rings 19 retain the abrasive blocks 15 in proper position in the tool so that smooth surfaces are produced during the honing operation. In this way better work will be produced with the use of the improved honing tool of the present invention than has been possible heretofore with known devices designed for a similar purpose.

During operation of the improved honing tool, the abrasive blocks 15 may shift their positions in the body 11 as the result of the action of the

springs 18 thereagainst, consequently the rings 19 should be of a flexible type and should have sufficient resiliency to at all times counteract the expansion of the springs 18 sufficiently to retain the abrasive blocks 15 in the desired position in the grooves 13 and to also prevent said abrasive blocks from being dislodged or misplaced from their respective grooves.

Since each abrasive element 15 is individually urged outwardly by its respective pair of springs 18, wear of the elements will not affect the operation of the tool to properly hone at one time a plurality of rifling grooves, and therefore all of the rifling will be honed smoothly and uniformly at one time by the operation of the tool in well known manner.

While I have described the invention in great detail and with respect to the present preferred form thereof, it is not desired to be limited thereto since changes and modifications may be made therein without departing from the spirit and scope of the invention. The invention may be embodied in other specific forms without departing from the essential characteristics thereof. The present embodiment is therefore to be considered in all respects as illustrative and not restrictive, the scope of the invention being indicated by the appended claims rather than by the

foregoing description, and all changes which come within the meaning and range of equivalency of the claims are therefore intended to be embraced therein.

Having thus described my invention, what I claim is:

A honing tool of the class described, comprising a cylindrical body, a plurality of spiral grooves formed longitudinally in the outer surface of said body, the ends of said grooves terminating at a distance from the ends of the body and being arcuate in form, a block of abrasive material mounted in each groove, said blocks of abrasive material having an outline corresponding in form substantially to the configuration of said spiral grooves and freely movable in the grooves, a pair of holes formed in the bottom of each groove, each hole being spaced from the end of said groove, a spring mounted in each hole and bearing against the under surface of a block of abrasive material for urging the block outwardly with respect to the body, a transverse slot formed in the outer surface of each abrasive block near the end thereof, and a flexible ring encircling said body and disposed in the alined slots at each end of said block for limiting the amount of outward movement thereof with respect to the body.

WILLIAM C. RICKRODE.
